CLAIM

The ornamental design for a display for advertisements, substantially as shown and described.

DESCRIPTION

FIG. 1 is a front perspective view of a display for advertisements showing my new design;

FIG. 2 is an enlarged fragmentary perspective view showing the upper right-hand corner of FIG. 1;

FIG. 3 is a bottom plan view of the entire display for advertisements;

FIG. 4 is a sectional view as seen along line 4—4 of FIG. 1.

The rear of the display for advertisements which is not shown is identical to the front as disclosed in FIG. 1.

FIG. 4

FIG. 3

FIG. 2
